METAL UMBRELLA

Maurice M. Harrison, Dallas, Tex.

Application June 16, 1958, Serial No. 51,359

Term of patent 14 years

(Cl. D88—3)

FIG. 1

FIG. 2

Fig. 1 is a perspective view of a metal umbrella, showing my design; and

Fig. 2 is a fragmentary view on a larger scale showing a portion of the periphery.

The essential feature of my design resides in the embossed scalloped effect on the downwardly turned periphery of the umbrella, with the meeting edges of the embossed scalloped design being located in the central part of the respective panels of the umbrella, as shown.

I claim:

The ornamental design for a metal umbrella, as shown and described.
